UNITED STATES PATENT OFFICE.

WILLIAM FRANKLIN LOUX, OF PHILADELPHIA, PENNSYLVANIA, ASSIGNOR TO
WILLIAM H. HORN & BROTHER, INCORPORATED, OF PHILADELPHIA, PENNSYLVANIA, A CORPORATION OF PENNSYLVANIA.

TRUSS.

1,191,805.

Specification of Letters Patent. Patented July 18, 1916.

Application filed April 30, 1914. Serial No. 835,500.

To all whom it may concern:

Be it known that I, WILLIAM FRANKLIN Loux, a citizen of the United States, residing in Philadelphia, Pennsylvania, have invented certain Improvements in Trusses, of which the following is a specification.

In trusses as commonly employed for the treatment of hernia, and particularly those used for double hernias, the resilient strip or spring is customarily open in front, and its ends, on which the truss pads are carried, are separably connected by a strap. In this form of truss there is at all times a likelihood that the pads will move or be placed 10 to one side or the other of the hernias by reason of alteration in the form of the body of the wearer or because of the careless application or adjustment of the truss.

In a second form of truss the resilient strip or spring opens at the back of the wearer, having its ends as above detachably connected by a strap, and while this has the advantage that the pads remain at the proper fixed distances apart, on the other 25 hand, by virtue of its construction, both pads necessarily have the same pressure applied to them. Moreover, since the front portion of the spring strip is relatively stiff, the pressure is "dead" and unvarying, depending largely on the tightness of adjustment of the strap.

One object of my invention, therefore, is to provide a truss which, while possessing the advantages of both of the above named 35 types, at the same time is of such construction that it may include springs of different strengths for acting on hernias of different severity with independent and different pressures.

Another object of the invention is to provide a truss in which the distance between the pads shall be fixed after they have been adjusted on their supporting structure, and in which the springs are capable of independent action, it being also desired that the construction shall be such that the act of applying the truss shall cause the pads to exert an effect on the hernias such as would be caused by the human hands in the act of 45 reducing the same. In other words, the pressure of the pads is first exerted at the lower parts of the hernial openings and is gradually increased upwardly as the

truss spring is brought in contact with the body.

These objects and other advantageous ends I secure as hereinafter set forth, reference being had to the accompanying drawing in which the figure is a perspective view illustrating a truss constructed according to my 55 invention.

In the above drawing 1 and 2 represent two U-shaped springs of strip material each having in one end an elongated slot 3 and connected at said slotted ends by a front 65 piece 4 to which they are hinged. On the opposite end of one of said springs is a strap 5 having a series of openings 6 for the reception of a suitable headed pin carried by the free end of the second spring. These free 70 ends of the springs constitute the back of the truss and respectively carry pressure or back pads 7 and 8 which may be of any desired construction and mounting although they are preferably so mounted as to have a 75 limited universal movement. The front or hernia pads 9 and 10 are each provided with a screw 11 passing through the slot 3 of one of the springs and arranged to permit its pad being adjusted toward and from the 80 other as may be desired. These hernia pads are of any suitable construction and mounting and are properly adjusted in fitting the truss to the person who is to wear the same by rotating them on the screws 11 as axes 85 and moving them toward or from each other until they occupy positions such as to suitably act on the hernias to be treated. Said screws are then tightened and in applying the truss the front pads 9 and 10 are first 90 placed over the hernias, whereupon the act of placing the pressure pads 7 and 8 upon the back of the patient so turns the springs 1 and 2 with their pads 9 and 10 upon the hinges or pivots connecting them to the 95 piece 4, as to cause these latter pads to move relatively toward each other in a sliding engagement with the body. Thereafter the free ends of the truss are connected by engaging the pin on the spring 2 with that 100 particular part of the strap 5 which will cause the truss to be properly and comfortably supported. Obviously, these springs 1 and 2 may be caused to exert different pressures upon the hernias engaged 105 by their pads 9 and 10 and for this purpose

may be made of different materials or dimensions or on the other hand may be given different primary shapes so as to attain the same end when placed upon the wearer.

5 One advantage of the above construction resides in the fact that it is not possible for the distances between the pads 9 and 10 to be varied either by carelessness of adjustment of the wearer or by reason of changes 10 in the shape of his body, while in addition, each spring acts upon the hernia covered by its pad in such a manner that it is practically independent of the other spring. Owing to this fact each pad has exerted upon it the 15 desired pressure although the action is a springy one, in contradistinction to that existing if the two ends of the springs 1 and 2 were rigidly connected as heretofore has been the case with trusses which open in the 20 back.

While in the drawing I have shown a front piece hinged to both of the truss springs 1 and 2, it will be understood that without departing from my invention one of 25 these hinges may be omitted and the springs be directly connected by means of a single

hinge. In any case the springs act independently of each other so that the device possesses all of the advantages above noted.

I claim:

1. The combination in a truss of two spring members each having a rigid piece connected to one end; a third rigid piece having its ends respectively hinged to said pieces on the spring members; hernia pads respectively mounted on the rigid pieces of the spring members adjacent their points of connection with the third rigid piece; and pressure pads respectively mounted on the spring members adjacent their free ends. 35

2. The combination in a truss of a rigid front piece; two spring members respectively hinged to said piece; and hernia pads mounted on the spring members adjacent their points of connection to the front-piece. 40

In testimony whereof, I have signed my name to this specification, in the presence of two subscribing witnesses.

WILLIAM FRANKLIN LOUX.
